UNITED STATES PATENT OFFICE.

WILLIAM K. BOOTH, OF CHICAGO, ILLINOIS, ASSIGNOR TO BOOTH-HALL COMPANY, OF CHICAGO, ILLINOIS, A CORPORATION OF ILLINOIS.

ELECTRIC FURNACE AND METHOD OF OPERATION.

1,244,415.

Specification of Letters Patent. Patented Oct. 23, 1917.

Application filed June 29, 1917. Serial No. 177,679.

To all whom it may concern:

Be it known that I, WILLIAM K. Booth, a citizen of the United States, residing at Chicago, in the county of Cook and State 5 of Illinois, have invented a new and useful Improvement in Electric Furnaces and Methods of Operation, of which the following is a specification.

This invention relates particularly to electric furnaces which operate normally by passing electric current between an upper electrode and a wall or hearth contact, and through the interposed charge which preferably is fused by the arcing of the electric 10 current.

The primary object of the invention is to provide an electric furnace which can be put into operation with facility and which will operate efficiently. A further object is 15 to provide an improved method of operating electric furnaces.

The accompanying drawings illustrate furnaces embodying the invention, operating on the single-phase, the two-phase, and 20 the tri-phase systems.

In the drawings—

Figure 1 is a diagrammatical view of a single-phase furnace embodying the invention; Fig. 2, a similar view of a two-phase furnace embodying the invention; Fig. 3, a similar view of a three-phase furnace embodying the invention; Fig. 4, a broken elevational view of the furnace shown in Fig. 1, illustrating somewhat conventionally 30 the automatically adjustable electrode employed; and Fig. 5, a similar view illustrating a manually adjustable auxiliary electrode employed.

Referring to Figs. 1, 4 and 5, illustrating 40 the preferred form of single-phase furnace, A designates a melting chamber provided with refractory walls which may be formed of any suitable fire bricks or refractory material, these walls, or the hearth portion of 45 the furnace, at least, being of a material which, while virtually non-conductive when cold, becomes relatively conductive when hot; B, a wall-contact embedded in the hearth near its inner surface, and preferably comprising an iron or steel grid filled with or 50 embedded in a block of carbonaceous material; C, an automatically adjustable main electrode which depends from the roof or arch into the melting-chamber; D, a manu-

ally adjustable, or withdrawable, auxiliary 55 electrode, which depends into the melting-chamber; E, the primary winding of a single-phase transformer; and F, the secondary winding of said transformer which has one terminal connected by a conductor G to the 60 main electrode and the other terminal connected by conductors H and H' to the wall-contact B and the auxiliary electrode D, respectively. As thus described, it will be understood that the wall-contact B and 65 auxiliary electrode D are connected to one side of the secondary circuit and thus are of the same polarity, and the main electrode C is connected to the other side of the secondary circuit and is of opposite polarity; 70 also, that the hearth provides a refractory facing, 1, for the wall-contact B, which facing becomes sufficiently conductive to carry the load only when the furnace is hot.

The furnace is shown provided with a 75 charging door K and a tap-hole L. In the furnace is the charge M which is to be melted or reduced. In melting scrap-metals, for illustration, the preferred method of operation is to lower the auxiliary electrode D 80 into contact with the charge and maintain an arc between the main electrode C and the charge M, as at 2. The current passes, therefore, between the upper main electrode and the (upper) auxiliary electrode through 85 the charge. The fused metal trickles to the hearth and collects at M', thus heating the refractory facing 1 of the wall-contact B and establishing the main circuit through 90 the hearth. After the preliminary heating 95 operation, the auxiliary contact D is preferably withdrawn sufficiently to throw it wholly out of operation, and the load is then carried wholly through the wall-contact.

The invention enables the wall-contact to be used to secure good distribution and efficiency and to avoid undue electrode complications, while still permitting the furnace to be preliminarily heated with the greatest 100 facility. In a single-phase system, the use of but one automatically regulated electrode is required for automatically stabilized operation, and the duty placed upon the manually adjustable or withdrawable auxiliary 105 electrode is so light as to obviate necessity of renewal, except at long intervals.

In Fig. 4 is illustrated a well-known form

of automatic regulating means for the main electrode C. Such means may comprise a vertically movable electrode-support N, whose vertical portion is equipped with a 5 rack operated by a pinion N' attached to a worm-wheel N² actuated by a worm N³ on the shaft of an electric motor N⁴. The motor is controlled by a circuit (not shown) in the usual manner, which operates to maintain 10 the proper arc at the main electrode, according to the current flowing in the main circuit.

In Fig. 5, manual adjusting means for the auxiliary electrode D is shown. Such 15 means may be like that shown in Fig. 4, except that the motor and its automatic controlling means may be omitted. The elements in Fig. 5 which correspond with similar elements in Fig. 4 are correspondingly 20 lettered. In this case, however, the shaft equipped with the worm N³ is operated by a bevel-gear N⁵ actuated by a bevel-pinion on a shaft equipped with a hand-wheel N⁶. Similar manual means may be employed 25 as an auxiliary adjusting means in connection with the mechanism shown in Fig. 4, if desired.

Fig. 2 represents the preferred form of a two-phase furnace embodying the invention. 30 A' represents the fusing-chamber; B', B², two wall-contacts embedded in the refractory hearth and substantially insulated from each other; C', C², two automatically regulated upper main electrodes; D', a manually 35 adjustable or withdrawable auxiliary electrode; E', the primary windings of a two-phase transformer or transformers so connected as to deliver a two-phase secondary current, the primary current being a three-phase alternating current, if desired; F', F², the secondary windings of the transformer device; G', a conductor connecting one terminal of one secondary phase to the main electrode C'; H, a conductor connecting the 40 other side or terminal of the same secondary phase to the wall-contact B'; G², a conductor connecting one terminal of the other secondary phase to the main electrode C²; H² and H³, conductors connecting the other terminal of the last-mentioned secondary phase to the wall-contact B² and the auxiliary electrode, respectively; and H⁴, a conductor equipped with a switch H⁵ and connecting the conductor H, to the conductor H², thus 45 bridging the space between the wall-contacts B' and B², during the preliminary heating operation. The effect is to connect the conductor H both to the wall-contact B' and the auxiliary electrode D', so that the latter will serve as a common return for both 50 secondary circuits during the operation of preliminarily heating the furnace to render the refractory facings 1^a and 1^b conductive. It may be noted here that the wall-contacts 55 are of large area so that the current spreads

in passing from the main electrodes to the hearth. Moreover, it will be observed that the currents of the two secondary circuits cross in the charge M when the main circuits are established, as indicated by the 70 dotted diagonal lines in Fig. 2.

In this case, also, it is preferred to maintain the auxiliary electrode D' in close contact with the charge M and establish arcs at 2, the current passing through the charge 75 to the auxiliary electrode D', during the preliminary heating operation. When the hearth becomes sufficiently conductive to carry the load, the switch H⁵ is opened and the auxiliary electrode D' is withdrawn 80 from operation.

The main electrodes C' and C² are preferably equipped with automatic regulating means of the character illustrated in Fig. 4; and the auxiliary electrode D' is preferably 85 equipped with manual adjusting means of the character shown in Fig. 5.

Fig. 3 represents the preferred form of a tri-phase furnace embodying the invention. A² represents the fusing-chamber; B³, a wall-contact embedded in the hearth; C³, C⁴, C⁵, automatically regulated main electrodes; D², a manually adjustable auxiliary electrode; E² the primary winding of a transformer device adapted to deliver a three-phase current; F³, F⁴, F⁵, the secondary windings of the transformer or suitably connected transformers; G³, G⁴, G⁵, conductors connecting one terminal of the three secondary phases to the main electrodes C³, 100 C⁴ and C⁵, respectively; and H⁶, H⁷, conductors connecting the other terminal of said phases to the wall, or hearth contact, B³, and auxiliary electrode D², respectively.

The main electrodes may be provided with 105 automatic regulating means of the character shown in Fig. 4; and the auxiliary electrode D² may be provided with the manual regulating means shown in Fig. 5. The transformer device may comprise a three-phase transformer, or a series of transformers so connected as to deliver a three-phase secondary current. In preliminarily heating the furnace, it is preferred to adjust the auxiliary electrode D² in contact with 110 the charge M, and to so adjust the main electrodes C³, C⁴ and C⁵ as to establish arcs 2. In preliminarily heating the furnace, the auxiliary electrode D² serves as a common return for the current from the three main electrodes. When the furnace becomes hot, the refractory facing 1^c of the wall-contact F becomes sufficiently conductive to carry the load, whereupon the auxiliary electrode D² is preferably withdrawn from operation. 115

The main upper electrodes ordinarily are composed chiefly of carbon, but any suitable material may be used; and any suitable lower main electrode or wall-contact may be employed. In the illustrations given, an 120

iron or steel grid having a carbonaceous block molded thereon is employed. The metal bars may extend to a water-cooled shank, or bar, to which the conductors may be attached, as indicated diagrammatically in Fig. 2. So, also, any suitable forms of electrode supporting and adjusting devices may be employed. Preferably, an alternating secondary current is employed for operating the furnace, but the invention is not to be considered as unnecessarily limited. So, also, it is preferred to operate with the auxiliary electrode in contact with the furnace charge during the preliminary heating of the furnace, thus avoiding arcing at the auxiliary electrode. Obviously, however, the invention is not limited to such mode of operation.

The improved furnace is of the greatest simplicity consistent with stabilized operation, is efficient in operation, and is capable of being placed in operation with the greatest facility. These advantages and other advantages possessed by the furnace will be readily appreciated by those skilled in the art.

The invention is applicable not only to the single-phase, two-phase and tri-phase systems, but also to any multi-phase system which it may be desirable to employ in furnace construction. The use of the invention obviates certain objections inherent in electric furnaces employing main electrodes of opposite polarity in the upper portion of the heating chamber for carrying on the normal operation of the furnace; and possesses decided advantages over the induction type of furnace. The invention renders unnecessary the use of heating resistances in the furnace-walls and special circuits therefor, for the purpose of preliminarily heating the furnace.

The foregoing detailed description has been given for clearness of understanding only, and no unnecessary limitation should be understood therefrom, but the appended claims should be construed as broadly as permissible in view of the prior art.

What I regard as new, and desire to secure by Letters Patent, is:

1. In an electric furnace, the combination of a heating chamber provided with a wall terminal, a co-acting main electrode of opposite polarity, and an auxiliary electrode of the same polarity as said wall terminal and adapted to serve in preliminarily heating the furnace.

2. In an electric furnace, the combination of a heating chamber having a wall terminal with a refractory facing which is conductive when hot, a co-acting main electrode of opposite polarity adapted to arc at the upper portion of the charge, and an auxiliary electrode of the same polarity as said wall terminal and adapted to contact with the upper

portion of the charge and co-act with said main electrode in preliminarily heating the furnace.

3. In an electric furnace, the combination of a heating chamber having a wall terminal with a refractory facing which is conductive when hot, a co-acting main electrode of opposite polarity adapted to arc at the upper portion of the charge, a withdrawable auxiliary electrode extending into the heating chamber near the upper portion of the charge, and a transformer having a secondary circuit with one terminal connected with said main electrode and another terminal connected with both said wall terminal and auxiliary electrode.

4. In an electric furnace, the combination of a heating chamber having a hearth provided with an embedded terminal faced with refractory material which is conductive when hot, said chamber having a top wall provided with openings, a main electrode depending through one of said openings and adapted to operate an arc at the upper portion of the charge, an auxiliary electrode depending through another opening in the top wall and adapted for ready withdrawal, and a transformer having a secondary circuit with one terminal joined to said main electrode and another terminal joined to both said wall terminal and said auxiliary electrode.

5. In an electric furnace, the combination of a heating chamber having a lower terminal, an upper main electrode equipped with automatic adjusting means, a readily withdrawable auxiliary upper electrode, and a transformer having a secondary circuit with one terminal joined to said main electrode and another terminal joined both to said lower terminal and said auxiliary electrode.

6. In a poly-phase electric furnace, the combination of a heating chamber having a hearth equipped with terminal means provided with a refractory facing which is conductive when hot, a plurality of upper main electrodes, an upper auxiliary electrode adapted to form a common return for the current from the main electrodes in preliminarily heating the furnace, and transformer means whose secondary circuits are connected on one side to said main electrodes and on the other side to said bottom terminal means and said auxiliary electrode.

7. The method of electric furnace operation which consists in using an auxiliary electrode in conjunction with the main electrode for heating the furnace and making the wall-contact sufficiently conductive and then using said main electrode and said wall-contact to carry on the operation of the furnace.

8. The method of operating an electric furnace having a wall-contact or contacts

with a refractory facing and an arcing main electrode or electrodes adapted to coact therewith when the furnace is hot, which consists in preliminarily heating the furnace by passing current through the charge in the furnace between said electrode or electrodes and an auxiliary electrode which serves as a pole in lieu of said wall-contact till the wall-contact becomes sufficiently conductive to carry the load, and thereupon withdrawing the auxiliary electrode from operation and causing the current to be carried wholly

through the charge to the furnace-wall and to the wall-contact or contacts.

9. In an electric furnace, the combination of a heating chamber provided with a wall terminal, a co-acting upper main electrode of opposite polarity, and an auxiliary electrode of the same polarity as the wall terminal, equipped with mechanical adjusting means, said auxiliary electrode adapted to co-act with said upper main electrode in preliminarily heating the furnace.

WILLIAM K. BOOTH.
